UNITED STATES PATENT OFFICE.

BENJAMIN CRABTREE CALDERWOOD, OF VALLEY FALLS, RHODE ISLAND, ASSIGNOR TO PRICE-CAMPBELL COTTON PICKER CORPORATION, OF NEW YORK, N. Y., A CORPORATION OF DELAWARE.

BAFFLE-PLATE.

1,222,733.

Specification of Letters Patent. Patented Apr. 17, 1917.

Application filed April 30, 1913. Serial No. 764,526.

To all whom it may concern:

Be it known that I, BENJAMIN CRABTREE CALDERWOOD, a citizen of the United States, residing at Valley Falls, in the county of Providence and State of Rhode Island, have invented certain new and useful Improvements in Baffle-Plates, of which the following is a specification.

My invention relates to improvements in baffle plates for cotton cleaners on cotton-picking machines whereby the baffle plate is so formed that it assumes the shape of an irregular triangle, one side of which is in the form of an arc of a circle, while the other forms an incline when placed in the cleaners down which the cotton doffed from the first of the two sections in the cleaners is directed onto the conveyer belt in the rear section, where a similar process of cleaning is gone through before the cotton is deposited into the proper receptacles. The cleaning processes and the functions of the baffle plate will be explained in a subsequent paragraph.

The arc of the baffle plate has a radius slightly larger than the card roller, and when in position the centers of both radii occur at the same point. The result is a comparatively small open adjustable space between the periphery of the card roller and the arc of the baffle plate, which has the following effect.

In the event of any seed cotton not being removed from the card roller by the combined fan and doffer, which will be described in a later paragraph, the cotton will be carried between the baffle plate and the card clothing of the card roller, the adjustable space previously mentioned will force the cotton onto the card clothing so that it will be carried back into the first section of the cleaners, and later doffed by aforesaid combined fan and doffer when it attains a certain point in relation to said combined fan and doffer.

The objects of my invention are: first, to provide means for depositing the seed cotton on the conveyer belt in the second or rear section of the cleaners after this has been treated in the first or forward section; and second, to provide against loss of the

cotton while in transit between the two sections of the cleaners.

In the accompanying drawings forming a part hereof,

Figure 1 is a side view of the cleaners with a portion cut away.

Figs. 2 and 3 are details of the baffle plate.

In the drawings, 1 is the elevator housing, which incloses the elevator belts which convey the picked cotton from the drums to the cleaner 2. 3 is the forward section of the cleaner, and 4 the rear section of it. The seed cotton, after leaving the elevator, is deposited on the first or forward conveyer belt 5, where it is opened and distributed evenly upon the surface of said conveyer belt 5, by the action of a breaker fan, not shown. From said conveyer belt 5 the cotton is next picked up by the action of the card roller 6. The cotton, adhering to the card roller, is carried on the periphery of this until at a predetermined point it is removed by the action of the combined fan and doffer 7, this fan and doffer also creating a strong current of air which blows dirt, sand, debris and foreign matter from out the cleaners.

The cotton, once removed from the card roller, is directed on the second or rear conveyer belt 8, which travels in the rear or last section of the cleaner, by the incline on the baffle plate 9 attached to the cleaner in the open space between the two conveyer belts 5 and 8. In the event of any seed cotton not being properly doffed it will be carried into the space 10 between the periphery of the card roller and the arc in the baffle plate, where it will be forced onto the card clothing and thus be brought back into the forward section of the cleaners and again be carried around by the card roller into the proper position for doffing.

The rear or last section of the cleaner, shown at 4, contains a mechanism similar in every detail to that contained in the first or forward section 3, thereby eliminating the necessity of describing the cleaning process a second time. Sufficient to state that the bulk of the cleaning is done in the forward section, which causes the rear section to as-

sume the function of a refining or finishing process.

The cotton, after cleaning, is deposited in the proper receptacles or containers through 5 the outlet 11. 12 is a holder for the baffle-plate 9, said holder in turn being attached to the cleaner bracket 13.

As will be seen from the arrows, the card roller rotates in a vertical plane, but in a 10 direction opposite to that of the combined fan-and-doffer, said fan-and-doffer rotating at a far higher velocity than the card roller. Also it will be seen that the conveyer belts travel in a direction which will carry the 15 cotton from forward to rear.

In case any seed cotton is retained by the card and is not doffed by the doffer 7, the member 9 operates to press this cotton into the card more firmly in order that it may be 20 doffed on its next trip around with the card, but such compression does not constitute such an entanglement of the cotton in the card as to render the action of the doffer 7 in any way insufficient for practical doffing. It 25 will be seen that the member or baffle-plate 9 which extends transversely across the machine, is held by one edge only. It is made of sheet metal and is therefore resilient. One of its inclined sides acts as an elastic

presser, while the other extending toward 30 the upper run of the belt 8 acts as a kind of chute.

What I claim is:

The combination of a card roller, a fan doffer, and an endless receiving belt, with a 35 transverse baffle plate approximately triangular in cross-section, one side being arced and elastic and held adjacent the periphery of the card roller, and the other side being below the fan doffer and extending toward 40 said belt, the free ends of the card teeth and the opposed surface of the baffle plate being slightly spaced apart, and the baffle plate serving to keep the cotton from falling from the card roller if any fails to be doffed from 45 the card roller by the fan doffer; the fan doffer being above the baffle plate and the baffle plate being located in front of the card roller with its main portion below the axis thereof.

In testimony whereof I have hereunto set my hand in the presence of two subscribing witnesses, this 25th day of April, 1913.

BENJAMIN CRABTREE CALDERWOOD.
